UNITED STATES PATENT OFFICE.

NELSON C. DURAND, OF NEWARK, NEW JERSEY, ASSIGNOR TO NEW JERSEY PATENT COMPANY, OF WEST ORANGE, NEW JERSEY, A CORPORATION OF NEW JERSEY.

DESIGN FOR A SPEAKING-TUBE FOR PHONOGRAHS.

59,543.

Specification for Design.

Patented Nov. 1, 1921.

Application filed July 27, 1921. Serial No. 488,017. Term of patent 7 years.

To all whom it may concern:

Be it known that I, NELSON C. DURAND, a citizen of the United States, residing at Newark, in the county of Essex and State of New Jersey, have invented a new, original, and ornamental Design for a Speaking-Tube for Phonographs, of which the following is a specification, reference being had

to the accompanying drawing, forming a part thereof.

The single figure is a view in perspective of a speaking tube showing my new design.

I claim:

The ornamental design for a speaking tube for phonographs, as shown.

NELSON C. DURAND.
